CLOTHES HANGER

Frank Ferrarelli, Cincinnati, Ohio

Application January 15, 1935, Serial No. 1,929

1 Claim. (Cl. 211—178)

The present invention relates to a clothes stand or costumer.

An object of the invention is to provide a clothes stand which normally functions as and is 5 similar in appearance to the conventional type of stand, but when occasion demands may be expanded to receive a relatively large quantity of clothes.

Another object of the invention is to provide a 10 clothes stand which, in contracted condition, occupies a minimum amount of floor space and in expanded condition is adapted to support a large amount of clothes, stably.

The embodiment of the invention is contemplated to be of use in small homes, apartments 15 or office rooms where floor space is in great demand, or where facilities for receiving large quantities of clothes are lacking.

In the drawings, Fig. 1 is an elevational view 20 of the preferred form of my invention.

Fig. 2 is an elevational view showing the invention in expanded position.

Fig. 3 is a fragmental view, part in cross-section showing the construction of the lower pivot 25 members.

Fig. 4 is a cross-section view showing the latch means.

Fig. 5 is a view taken in line 5—5 of Fig. 3.

Fig. 6 is a fragmental perspective view of a 30 modified form of the invention.

Fig. 7 is a modified form of the invention, part in cross-section showing a pivot means.

Fig. 8 is a perspective view of the pivot means shown in Fig. 7.

Fig. 9 is an elevational view of a clothes 35 hanger.

My invention consists of a standard 12 mounted upon a base or leg carriage 13, the standard preferably forming a central section of the base 40 to effect a rigid structure. Two vertically swinging posts 14 and 15 are substantially the same length as the standard, and normally abut it; latch means 16 being provided to secure the posts and standard in the abutting relationship.

Two links 17 and 18 having hinges 19 and 20 45 at their extremities connect the posts and the standard thus allowing the posts to swing outwardly and rest upon the supporting surface of the base. In expanded condition (Fig. 2) the links are in a horizontal position, the link 17 then providing a rack for hanging a large quantity of clothes.

A cap 21 positioned upon the upper end of the standard carries two latch catches 22. Spring 50 latches 23 mounted on the posts, and having

elongated release wires 24 are adapted to engage latch catches 22 and are employed to re-enforce the upper end of the posts when clothes are hung on brackets 25. Hangers 26 are mounted on the standard. The cap 21 may also carry a hat hanger 27 formed of heavy gauge wire supports which are clamped to a base 28 at their inner ends and at their outer ends form hanger means for receiving hats and the like. The base 28 may be pivoted to the cap 21. 10

A modified form of my device (Fig. 6) consists of a rectangular standard 30 having elongated longitudinal grooves 31 at its opposite corners. Posts 32 and 33 are connected to the standard by links 34 and 35. The links at their 15 extremities carry hinges as at 36 and 37. Latch means 38 similar to latch means 16 (Fig. 4) retain the posts in normal or closed relationship. By this method of construction the clothes hanging brackets 39 are positioned on the standard 20 and are not disturbed when the posts are moved to expanded position.

Another modified form of my invention, (Fig. 7) is a method by which the standard 12 and posts 14 and 15 are pivoted about the base or 25 leg carriage 13. The pivot means consists of a substantially square plate 40 carrying an annular groove or ball bearing racer 41 which is fastened to the vertical sides of the base or leg carriage 13 by screws or bolts run through apertures in vertical lugs 42. A top plate 43 carries a ball bearing racer 44 and a stem 45 which is received in an aperture 46. Bolt 47 securely holds the plates in rigid relationship. Lugs 48 are provided to secure the standard 12 to the 30 plate 43. The hinge members for links 17 and 18 are bolted to the top plate member. Rollers 49 and 50 are inset in the bases of the posts to allow the posts, in expanded position, to rotate on the supporting surface of the base. 40

To increase the capacity of the clothes stand a hanger 51 may be screwed to the standard 12. This hanger is provided with a plurality of brackets 52 extending from an arm 53 which is at an angle with the standard. A brace member 54 holds the arm rigid. 45

What I claim is:

A clothes stand for hanging full length garments comprising an elevated base having a plurality of legs, a rectangular standard positioned 50 on the base, two vertically swinging posts normally abutting parallel faces of the standard to simulate the appearance of an integral standard, latch means adapted to retain the posts in abutting relationship, hinge means consisting of 55

connecting links pivotally engaging the post and the standard at their extremities, the vertical height of the base and also the distance between the lower end of the post and the lower hinge means being equal to the length of the link, the standard containing recesses in its abutting faces to receive the links, said hinge means being

adapted to allow the posts to swing outwardly in a plane at right angles to the abutting faces of the standard and to allow the posts to rest upon the supporting plane of the base, the top links then forming a rack for hanging garments. 5

FRANK FERRARELLI.
